MEANS FOR COUNTING, PORTIONING, AND
PACKING MATTER AS TABLETS, PILLS,
AND THE LIKE

Morten Hansen, Oslo, Norway

Application September 19, 1938, Serial No. 230,706
In Norway September 20, 1937

11 Claims. (Cl. 107—4)

The present invention relates to means for counting material such as tablets and pills for medicinal purposes or for other use, and further to means for packing such counted material in bottles, boxes or similar containers used for this type of goods.

The expression "tablets and pills" in the present description of the invention is intended to refer to any type of small articles, generally manufactured by pressing or moulding a pulverulent substance.

When such tablets have been made, it is usually necessary to apportion these tablets or pills for packing in boxes or other containers in different quantities. As long as the said tablets have a spherical or cylindrical shape, this apportioning of the tablets does not involve many difficulties due to the fact that means for automatically counting tablets of these shapes has been provided for a long time and is working satisfactorily, for instance by the use of centrifugal force which makes it possible to line the tablets up in rows, from where they are easily transferred to the containers.

The present invention relates to a perfect automatic machine which is adapted for counting and apportioning tablets of any shape without manual labour.

This invention also relates to means which makes it possible to give the tablets a finished surface and to remove from the tablets any edges and dust in such way that the tablets in counted portions will leave the counting machine in perfect shape ready for packing, without having to be touched by any persons.

One object of this invention is to provide means which may be arranged directly in combination with a press for forming such tablets of pulverulent material. Such presses may be of well known construction and comprise a rotating table and a number of pistons, arranged to rotate with the same. Such pistons are arranged as well above as below the table and are made to co-act in pressing the tablets in moulds in the table, the pressing taking place in such a way that as a pulverulent mass is fed to the said moulds, the pistons are pressed against each other in the said moulds, and the tablets are shaped.

When the pressing of a tablet has been finished, the pressing machine is usually arranged in such a way that the piston on top of the table will be raised above the same, and the piston below the table will be raised to push the pressed tablet up to a level above the surface of the said

table. One object of this invention is to provide means which is adapted at this moment to deliver the tablet from the table to a preliminary container which may be shaped as a channel. The 5 said preliminary reservoir or container is according to the invention provided with a gate which is in working connection or synchronised with the said delivering means in such a way that when a predetermined given number of the tablets has been delivered from the press to the said preliminary reservoir, the said gate will be opened, whereby the said quantity of tablets may be delivered directly to a packing machine or may be delivered to other means which is to give 10 the tablets a finish.

In connection with the above described means there may be arranged a receiver which is adapted to collect the portions as delivered from the preliminary reservoir and to keep the said portion until a certain number of such portions 15 has been received, whereby means are incorporated with the said receiver adapted to empty this in synchronism with the working of the press in such a way that a given multiple of the number of tablets gathered in the preliminary reservoir will be delivered from the said receiver. Thus, if for instance the counting mechanism in 20 direct connection with the press is adjusted to deliver 20 tablets to the preliminary reservoir between each time this is emptied, the said receiver may be adjusted in such a way that 5 such portions are gathered between each emptying, whereby the said receiver will deliver 100 tablets at the time, for instance to the packing machine. 25 The controlling means which may be used for controlling the action of the said receiver is no part of the present invention, due to the fact that any man skilled in the art may be able to choose suitable automatic operating equipment for controlling the said receiver in synchronism with the press or the first mentioned means for delivering the tablets as they are being manufactured.

It is preferred according to this invention to 30 combine the counting means with means for dusting and finishing the surface of the tablets manufactured. This dusting and removing of possible grades on the edges of the tablets may be performed in a rotating perforated cylinder, 35 having within itself a helically arranged wall which will form a screw-thread passage for the tablets from the inlet to the outlet end of the same. When the tablets are fed to the inlet end of this cylinder and this is set in rotation, the 40 portion of tablets will be made to move through

the same and be finished on the surface and ridded of its dust. From the outlet end of this drum the tablets may then be delivered to the above mentioned receiver or directly to the packing apparatus.

One may also substitute for the above mentioned cylinder a dusting and finishing apparatus, driven by means of vacuum. Such apparatus is well known per se and consists usually in a hollow upright container with an opening at the lower end and a connection to a vacuum pipe at the upper end, a screen being provided close to the upper end for preventing the matter from being drawn into the vacuum pipe. If such apparatus is arranged in connection with the said preliminary reservoir so that the tablets will be delivered from this to the inlet end of the vacuum pipe, the tablets will be sucked up into the same and be violently agitated against the screen at the upper end of the same. When a suitable treatment of the tablets has been finished, the vacuum may be broken and the tablets will drop out through the pipe and may be taken up in the above mentioned receiver for the purpose of multiplying the number of tablets in each portion or to the packing machine.

The above described combination of the means for counting, portioning and finishing of tablets can in suitable way be controlled by mechanical, pneumatic or electrical means, this means being arranged in such a way—if for instance electromagnetic means are chosen—that a controller will energize all the electromagnets at the same time, whereby the different operating mechanisms will be adjusted from normal position, i. e. the position which they will take when the magnets are demagnetized, to another position for transferring the portions of tablets to the next working place for the same.

At a given time the situation may for instance be, that one portion of tablets is being treated in the vacuum apparatus and one full portion has been gathered in the preliminary reservoir. At this moment the electrical contacts are closed and the magnets energized; the magnets must then be arranged in such a way that the tablets in the preliminary reservoir will be released to fall out of this; at the same time another magnet must break the vacuum in the vacuum pipe, in such a way that the tablets in the finishing apparatus will fall out and be gathered in the receiver or other means in connection with the packing apparatus. Finally special means may be arranged to transfer the tablets from the outlet of the preliminary receiver, to the inlet end of the vacuum pipe, so that this latter portion—when the electric connection is broken and the vacuum is again established in the vacuum pipe—will be sucked up into the same for treatment. While this portion of tablets is being treated in the vacuum pipe, a new portion of tablets is being gathered in the preliminary reservoir.

A further object of the present invention is to provide suitable means in combination with an above mentioned portioning apparatus for the packing of the portions thus counted into tubes, boxes, bottles or the like containers without the help of manual labour.

For this object the invention comprises two conveyors, one serving to convey the portions towards the point where the same are to be filled into the containers, the other serving to convey the empty containers to this point.

Of primary importance there is according to this invention arranged a feeler member which is positioned so that it will be influenced by the portions of matter being conveyed by the former conveyor in such a way that it by means of suitable mechanism will control the movements of the latter conveyor to cause an empty container exactly to come to standstill under the discharge end of the former conveyor, when one portion of matter is to be discharged.

The invention further comprises specially constructed means, suitable for obtaining the above mentioned effect as well as means which are provided for establishing a shaking action of the container as the portion of matter is filled therein.

These different means will be further described in the following description which in connection with the drawings illustrates one way in which the present invention may be worked.

Fig. 1 illustrates diagrammatically a part of the machine according to the invention.

Fig. 2 illustrates the construction shown in the left-hand portion of Fig. 1 in a somewhat different working position.

Fig. 3 illustrates a modified construction of a dusting apparatus diagrammatically.

Fig. 4 is a plan view of the tablet press with parts broken away.

Fig. 5 is a view from the side of that part of the machine which is used for packing the portions.

Fig. 6 is a view of Fig. 5 seen from above.

In the drawings, 1, 2, 3, 4, 5, 6, 7 denote the different parts of the usual press for making tablets, which machine in the following description as a whole will be called 8 viz. 1 denoting the shaft of the machine, 2 the table with the mould, 3 the pistons on the underside of the table, 4 the guiding disk or ring for the pistons 5, 6 lifting rods for the pistons 5, 7 a guiding cam for the pistons on top of the table, 7^b a guiding cam for the pistons on the underside of the table and 14^a a ruler for guiding the tablets off the table.

On the side of the machine 8, a shaft 9 is journalled, which shaft is provided with spokes or arms 10, arranged at such a level in relation to the machine that they will exactly pass in over the table 2 and reach so far towards the centre of same that the inner end of these arms will extend to the inside of the circle in which the pistons 3 and 5 are working.

On the shaft 9 there may further be arranged arms or spokes 12 which project in over the disk 4 on which there may be arranged projections 13 which will co-operate with the arms 12 and provide that the shaft 9 with the arms 12 or spokes 10 will rotate with a definite speed in relation to the press 8.

Up to the edge of the table 2 there is arranged a channel 14 in such a way that the tablets 15 which have been lifted to the overside of the table by the pistons 3, will be caught by one of the spokes 10 and pushed into the channel 14 and thus be gathered resting against the gate 16. The gate 16 may be pivotally carried by a shaft 17 and may be provided with an extension in the opposite direction carrying a gate 18, in such a way that the gate 18 will close the admission to the lower part of the channel 14, when the gate 16 is open. The opening of the gate 16 respectively the closing of the gate 18 may be actuated by means of an electromagnet 19 which is controlled by a relay 22 which will be further described below. The closing of the gate

16 respectively the opening of the gate 18 may preferably take place under the action of gravity.

At the other end of the channel 14 there is arranged a channel or pipe 23 in which there may be arranged dust gathering means 150 which may be connected to a vacuum pipe, and under the end of the pipe 23 there is arranged a basket 24 which is supported by or constructed as a pendulum, the upper end of the pendulum rod 25 being pivotally fixed at 26. Adjacent to the lower end of the pipe 23 there is arranged a pipe 27 which at the upper end has a hollow container 28 which is covered by a perforated plate 29. From the hollow container 28 through the perforated plate 29 connection is made to a vacuum pipe 30 in which a baffle 31 for the breaking of the vacuum is provided. The basket 24 is hung in such a way that under the action of gravity it will normally take a position under the lower end of the pipe 27. At the same time it is in working connection with the armature of an electromagnet 32, which through the means of leads 33, 34 is controlled by a relay 22. This control mechanism is arranged in such a way that the basket 24, where the electromagnet is energized, will swing over to the right side in Fig. 2 and take a position directly under the outlet of the pipe 23, while the same—when the power is taken off the electro-magnet 32—under the influence of gravity will swing back to its initial position under the pipe 27. The baffle 31 over the hollow container 28 is provided with an arm 35 having a curved armature core 36 which may be actuated by means of an electromagnet 37 which through leads 38 and 39 is controlled by the relay 22 in such a way that the baffle 31 will open when the electro-magnet 37 is fed with electric power, and be closed when the electro-magnet is demagnetized.

The relay 22 may work on low tension electric power or directly on net potential. If a low tension power is used, this may comprise a source of power 40, a contact member 41 which is stationarily fixed on the machine 8, and further a contact member 42 which co-operates with the former and is fixed to the rotating table 2 on the press 8 or a part thereof, the contact-member 41 being in connection with the source of power 40 by means of a lead 43, while the relay 22 is in connection with the source of power 40 on one side and with the frame of the machine and the contact 42 by means of the leads 44, 45 on the other side.

The machine above described will now act in the following way:

The table 15 which is just ready from the press and has been raised to the upper surface of the table 2, is caught by the spoke 10 and pushed down into the preliminary reservoir or channel 14, where it will be stopped against the gate 16. When the machine 8 has completed one rotation, contact will be made between the contact members 42, 41, whereby the relay 22 will cause the magnets 19, 32 and 37 to be energized. The basket 24 will be swung over to the right side on the drawings, the tablets 15'—which rest in the preliminary reservoir 14—will fall out from this and be gathered in the basket 24, and the tablets 15''—which at the present moment are being dusted in the vacuum container 28—will fall out of this and will be received in the receiver 45 shown in Figs. 5 and 6, or directly in the conveyor 52 shown in the same figures. At the same time, the tablets which have been gathered on top of the gate 16 will be trans-

ferred to the basket 24, and the gate 18 will be closed, thereby preventing tablets which are being manufactured while this transfer takes place from passing the open gate 16 and entering the basket 24. When the contact members 42 and 41 get out of contact with each other, the electromagnets will lose their power, the gate 16 will be closed, and will at once receive the tablets which meanwhile have gathered on the top side of the gate 18, the basket 24 will swing over to the left, and the vacuum in the pipe 27 will through the perforated bottom in this basket pull the tablets 15' up into the vacuum container 28, where they under heavy agitation will be ridded of their dust and grades.

One may—as it will appear from the introduction to the present description—use a dusting apparatus of a somewhat different construction. In Fig. 3 this modification is illustrated. The modified duster comprises a perforated cylinder 97 with a helically arranged inner wall 98. The portion 15' of tablets from the preliminary reservoir 14 is fed to the right end of this cylinder, and as it is rotating, this portion will by the thread-shaped wall 98 be fed towards the left side of the cylinder. The tablets will during this movement be exposed to agitation, which will rid them of dust and grades which will fall out of the cylinder 97. From the outlet of the pipe 27 or from the cylinder 97 the finished portion of matter may be directly transferred to a conveyor, or may as shown in Figs. 5 and 6 be transferred to a receiver 45.

At the outlet 46 of the receiver 45 there may be arranged a gate 47 which for instance under the action of an electro-magnet 148 can be lifted up at certain predetermined intervals, as for instance under the influence of a relay 48, which is controlled by suitable means on the press itself in such a way that for instance 10 portions of tablets 15 from the outlet 27 may be received each time the gate 47 is lifted by the electro-magnet 148.

On drums 49 and 50 there is carried an endless belt-conveyor 52. The tablets from the receiver will thus from the gate 47 be delivered to this belt and will by this be carried to the outlet end 51, where they will be dumped into a funnel 75.

Another conveyor 53, which may be formed as a table rotatably supported in the bearing 54 by means of a shaft 55 is arranged at the end of the conveyor 52. From the same driving means 56 which through the shaft 57 drives the conveyor 42, a belt 58 is arranged to a pulley 59 which through the shaft 60 and the friction roller 61 in contact with the conveyor 53 provides for the rotation of the same. In the conveyor 53 there is a number of pockets 62, shaped in such way that they may serve to receive the containers where-in the tablets are to be packed. The conveyor 53 is along its periphery provided with a number of extending arms 63, and under the conveyor a locking member 64 is arranged, which may come in mesh with these arms and prevent the rotation of the conveyor 53. The locking or checking mechanism 64 may comprise an electro-magnet 65 which, when it is energized, will pull the checking means 64 down against the action of a screw spring 66. The electro-magnet 65 is fed with power from an electric source 67 through leads 68 which go directly to the electro-magnet 65, and a lead 69 which goes to a contact mechanism 70, from which a lead 71 extends back to the electro-magnet.

The contact mechanism 70 is controlled by a

feeler 72 which rests against the conveyor 52 and is actuated by the portions 15 with pills which this conveyor carried.

In the embodiment shown in the drawings, the feeler 72 acts in that way that when a portion of pills 15 passes in under the same, it will be lifted about its swinging point 73 in such a way that contact is made by the contact means 10. The locking member 64 will thus be pulled back and the friction roller 81 will rotate the conveyor 53.

As soon as the portion 15 has passed the feeler 12, the contact will again be opened at 10 and the locking member 64 will be raised to stop the conveyor 53 when it has been moved around until the next arm 63 will mesh with the locking member 64. This means is arranged in such a way that the place where the conveyor will stop will be exactly thus that one empty container will stop under the funnel 75 so that one portion 15, when it passes over the outlet 51 from the conveyor 52 through the funnel, will pass down into the container 74.

The conveyor 53 will rest, until a new portion 15 will pass under the feeler 72, whereafter the conveyor 53 in the same way as above described will make a step forward to feed a new empty container in under the funnel 75.

Above the conveyor 52 it may be preferable to arrange a number of straight-edged guiding members 76, 77, 78 with an angle to the axis of the conveyor and with the inner end pointing in the direction of movement for the purpose of lining up the portions of pills as they are being carried towards the outlet end of the conveyor.

In the conveyor 53, there may thus manually be placed a number of empty containers 74, the pockets 62 on the underside being closed by a stationary plate 79 which may be supported by arms 80.

When the containers have been filled with tablets under the funnel 15 and the conveyor 53 stepwards moves on, the cover or lid 81 on the containers may be partly closed by means of a straight-edge 82 which is arranged stationary and projects in over the conveyor 53. In order to close the lids on the containers entirely, a roller 83 may be arranged for instance on the shaft 60 in such a way that it will roll over the partly closed containers and completely close their lids.

When the containers have been closed, they must be removed from the conveyor 53, and this may for instance be done thereby that the plate 79 is provided with an aperture 84 in such a way that when the container reaches a certain point, they will drop out through the aperture and leave the machine, for instance on an incline 85.

In order to insure a complete filling of the containers, it is preferred to arrange some shaking means for the containers at that position where they are being filled. Such shaking means may for instance be provided by means of a vibrating rod 86, which is held in vibration for instance by means of an electro-magnet 87 which is fed by alternating current.

By means of the feeler 72, one will obtain an accurate transfer of the portions of matter from the conveyor 52 to the containers without needing to undertake any regulations or care when the counting machine is delivering larger or smaller quantities of pills at larger or smaller time intervals.

One will thus be able to use the apparatus without adjustment for the packing of portions of 20 tablets or for the packing of portions of 100 tablets, even though the time between the portions

in the latter case will be five times as long as in the former case. The only adjustment which is needed, is a re-setting of the controlling means for the relay 48.

One must further be aware of the fact that the type of conveyors which has been chosen in the present embodiment for the purpose of illustrating the invention, does not in any way limit the scope of the same, as it is evident that any type of conveyors may be used in combination for obtaining the same result under the control of similar controlling mechanism.

I claim:

1. Improvement in means for counting and apportioning matter as tablets or pills of any kind and shape, as they are delivered shaped from a press, comprising a reservoir, means for moving each tablet immediately as ready from said press to said reservoir, means synchronized with said moving means, adapted at predetermined intervals to empty the said reservoir, a second reservoir, adapted to receive the tablets from said first mentioned reservoir, and means in connection with the said second reservoir adapted to agitate the tablets, when received in the same.

2. Means according to claim 1, in which said second reservoir is constructed as a cylinder made of perforated material and having mounted therein a helically formed wall forming a screw-thread passage through the said cylinder.

3. Means according to claim 1, in which the second reservoir is formed as an upright hollow body closed at the upper end by a perforated plate, means connected to this end of the reservoir adapted to establish a vacuum in the said reservoir.

4. Means according to claim 1, in which the second reservoir is formed as an upright hollow body closed at the upper end by a perforated plate, means connected to this end of the reservoir adapted to establish a vacuum in the said reservoir, and means adapted to receive the tablets from said first mentioned reservoir and transport them to said second reservoir.

5. Means according to claim 1, in which the second reservoir is formed as an upright hollow body closed at the upper end by a perforated plate, means connected to this end of the reservoir adapted to establish a vacuum in the said reservoir, and means adapted to receive the tablets from said first mentioned reservoir and transport them to said second reservoir, said means comprising a container supported by a pendulum and adapted to swing from under the outlet of said first mentioned reservoir to under the inlet of said second reservoir.

6. Means according to claim 1, in which said second reservoir is formed as an upright hollow body closed at the upper end by a perforated plate, means connected to this end of the reservoir adapted to establish a vacuum in the said reservoir, and means adapted to break the said vacuum for the purpose of releasing the tablets therein.

7. Means according to claim 1, in which said second reservoir is formed as an upright hollow body closed at the upper end by a perforated plate, means connected to this end of the reservoir adapted to establish a vacuum in the said reservoir, and a baffle in the upper end of the said second reservoir adapted to break the vacuum in order to release the tablets therein.

8. Means for counting material such as tablets as they are delivered from a forming press, com-

prising means adapted to deliver the tablets from said press, a reservoir adapted to receive the same as delivered and having a gate adapted to be opened at intervals, another gate nearer said press adapted to be closed when said first mentioned gate is opened and vice versa, a second upright hollow reservoir capable of being placed under a vacuum, a transporter mounted oscillatably adapted to receive the tablets from said first mentioned reservoir and to transport them to the underside of said second reservoir, a baffle in said second reservoir adapted to break said vacuum, electromagnetic means arranged to control the movements of the said gates, the said swinging transporter and the said baffle and a controller synchronized with the working operation of said press adapted to close and open the circuits to the said electromagnets in such a way that the gate from said first mentioned reservoir will be opened when a predetermined number of tablets has been delivered thereto, whereby the second gate is closed to prevent further deliveries of tablets to the said reservoir until the former gate is again closed, the transporter swinging from the former to the latter reservoir, when it has received a portion of tablets, and back again when it has delivered same to the latter reservoir, and the baffle in the second reservoir will be opened to break the vacuum and release the tablets therein before the transporter returns with a new portion of tablets.

9. Improvement in means for counting and apportioning material such as tablets or pills of any kind and shape as they are delivered shaped

5 from a press, comprising a reservoir, means for moving each tablet immediately as ready from said press to said reservoir, means synchronized with the said moving means adapted at predetermined intervals to empty the said reservoir, means adapted to receive a plurality of tablets and adapted to deliver a predetermined number of such tablets at a time.

10. Improvement in means for counting and apportioning material such as tablets or pills of any kind and shape as they are delivered shaped from a press, comprising a reservoir means for moving each tablet immediately as ready from said press to said reservoir, means synchronized with said moving means adapted at predetermined intervals to empty the said reservoir, means adapted to receive a plurality of tablets and adapted to deliver a predetermined number of such tablets at a time, a conveyor adjacent to the said receiver adapted to receive such tablets and to convey the same to a place of packing.

11. Improvement in means for counting and apportioning material such as tablets or pills of any kind and shape as they are delivered shaped from a press, comprising a reservoir, means for moving each tablet immediately as ready from said press to said reservoir and means synchronized with said moving means adapted at predetermined intervals to empty the said reservoir having a cross sectional area more than twice as large as the largest cross sectional area of the tablets being made.

MORTEN HANSEN.
